Primary Examiner — Rashida Johnson(74) Attorney, Agent, or Firm — Mark Terry(57) CLAIM

The ornamental design for a robe, as shown and described.

DESCRIPTION

FIG. 1 is a front perspective view of a robe, showing the new design;

FIG. 2 is a rear perspective view thereof;

FIG. 3 is a front side view thereof;

FIG. 4 is a right side view of thereof;

FIG. 5 is a top view thereof;

FIG. 6 is a rear view thereof;

FIG. 7 is a left view thereof; and,

FIG. 8 is a bottom view thereof.

The broken lines shown throughout the views represent stitching.
